UNITED STATES PATENT OFFICE

JOSIAH WILLIAM APPLETON, OF ROCKLAND, MASSACHUSETTS, ASSIGNOR TO EMERSON SHOE MANUFACTURING COMPANY, OF ROCKLAND, MASSACHUSETTS, A CORPORATION OF MASSACHUSETTS

SHANK PIECE

Application filed November 5, 1927. Serial No. 231,253.

This invention relates to shank pieces for shoes and particularly to shank pieces of the type relied upon to shape the shoe bottom and to conform the contour of the insole to the shape of the last bottom, in addition to stiffening the shank of the shoe.

With such purpose in view, my invention contemplates the provision of a shank piece shaped in general to act as a filler for the shoe bottom and being thickened at one edge to build up the insole at a corresponding point.

A further feature of the invention consists in interengaging the metal stiffener with the body part of the shank in such manner as to maintain the forward edge of the metal stiffener out of contact with the outsole, so that in long continued wear there shall be no danger of the metal edge cutting its way out through the outsole.

It is within the scope of my invention to include in my novel shank piece a metatarsal pad and, when this is included, it is disposed at the forward end of the shank preferably covering the end of the metal stiffener which projects upon the upper or inner surface of the shank.

Inasmuch as the contour of the insole and organization of the shoe is determined in large measure by my novel shank, the shoe structure which includes a shank shaped to fill the bottom, to build up the insole at desired points and to stiffen the outsole is also within the scope of my invention.

These and other features of my invention will be best understood and appreciated from the following description of a preferred embodiment thereof selected for purposes of illustration and shown in the accompanying drawings, in which:

Fig. 1 is a plan view of the body portion of the shank piece.

Fig. 2 is a fragmentary sectional view on an enlarged scale of the part shown in Fig. 1.

Fig. 3 is a plan view of the complete shank piece.

Fig. 4 is a sectional view on line 4-4 of Fig. 3, and

Fig. 5 is a sectional view of the sole bottom with my novel shank piece incorporated therein.

The body portion 10 of the shank piece is preferably of sole leather, leather board or fibre cut to the desired shape but might be of molded material. Its marginal contour corresponds in general to the heel seat and shank portions of a shoe bottom between the insole ribs or the lasted margin of the upper and it is extended transversely at its forward end to correspond to the widened portion of the bottom approaching the ball line. This lateral enlargement is non-symmetrical, being more pronounced on the inside shank edge. It will be noted also by reference to Fig. 4 that the inside shank edge of the body portion 10 is thickened. This is for the purpose of building up the insole at a corresponding point to form a leveled bottom for an outsole and thus cause the insole to fit the last bottom and the foot of the wearer.

The body portion 10 is provided with an oblique transverse slit 12 adjacent to its forward end through which may be passed the forward end of the metal stiffener 14. The metal stiffener 14 is made of sheet metal molded to the required shape and preferably convex in cross section as shown in Fig. 4. At its rear end it is provided with perforations 16 by which it may be tacked in place upon the lower or outer surface of the body member 10 of the shank piece. Its forward end is anchored in place by being passed through the slit 12, as will be apparent from an inspection of Fig. 3.

When it is desired to incorporate a metatarsal pad in the shank a pad 18 of sponge rubber or other flexible material is assembled in the shank and may have a portion of its periphery drawn into the slit 12 above the metal stiffener 14. This location not only retains the pad in place but provides additional protection between the forward edge of the stiffener and the surface of the insole. The pad in this position guards the insole against being cut by the metal edge of the stiffener while the body portion 10 similarly guards the outsole as already explained. In assembling the shank above described in a shoe the upper or inner face thereof may be cemented to the outer surface of the insole 20 and this includes the pad 18, or the shank

may be held in place by a tack. The outsole 22 is then laid and stitched in the usual manner, the body of the steel stiffener being located upon the outsole surface except at its forward end where it passes through the slit in the body of the shank piece. It will be seen that the inside shank portion of the insole 20 is built up under the corresponding portion of the arch of the wearer's foot and that a curved projection is formed in the insole under the ball of the foot by the metatarsal pad 18, also that the outsole is stiffened and given a characteristic shape by the shank piece.

15 The nature of my invention will be apparent from the foregoing description, but I wish to point out particularly its importance from the standpoint of practical shoe making. The shank by its novel and unusual construction incorporates more desirable features in one commercial unit than heretofore and makes practicable the production of corrective shoes in quantity. To illustrate,—when an upper is lasted over the insole the upper 20 leather, counter lining, and stays form a hollow or pocket under the heel seat, which, when depressed by putting on the heel often causes a hollow in the heel seat surface. The leather or body portion of my shank by its 25 peculiar form fills this space, not with metal but with material through which the heel nails can be driven. It then continues to the longitudinal arch of the foot and being of leather or similar material it can be skived, 30 molded or otherwise shaped in form so that it exactly fits the last bottom on which it is to be used. If the last requires a high curve the body of the shank is shaped so as to fit that curve and if the last requires a low arch 35 the same rule applies but the steel stiffener may remain the same. The body of the shank forms an even surface transversely from seam to seam, requiring no filling and leaving no pockets or air spaces between the 40 outer sole and insole at this point. The molded form of the steel piece being on the under side permits the use of a molded outsole. Thus the under side of the complete shank is a perfect fit for the outsole and the 45 upper side is a perfect fit for the arch of the wearer's foot.

50 Thus having described my invention, I claim:

1. A shank piece for shoes comprising a 55 body member slotted near its forward end, a metal stiffener disposed upon the lower surface thereof but passing through the slit at its forward end so that its forward edge lies above the body member and is maintained out of contact with the outsole.

2. A shank piece for shoes comprising a 60 body portion thickened at one edge to build up the insole at a corresponding point, enlarged transversely at its forward end to fill 65 the shoe bottom, and slotted in said enlarged

portion, a metal stiffener tacked to the body portion at its rear end and anchored at its forward end by passing into the slit and a metatarsal pad anchored by the slit.

3. A shank piece for shoes comprising a 70 body member shaped to fill the shank portion of the shoe bottom and being thicker at its inside shank edge than at its outside shank edge to build up the corresponding portion of the insole, and a metal stiffener located upon the lower surface of the body member except at its forward edge where it passes through the body member and lies upon its inner or upper surface.

4. A shoe construction including a shank 75 piece having a body portion thickened at its inside shank edge, a metal stiffener interengaged with the body portion at its forward end and a metatarsal pad at the forward end of the stiffener, together with an insole built 80 up at its inside shank edge by the corresponding thickened edge of the shank body portion to form a leveled bottom for an outsole, and an outsole maintained in engagement with the body portion of the shank piece 85 and the metal stiffener except at the forward edge of the latter.

5. A shoe construction including an insole, a molded metal stiffener, a shank body shaped at its under side to fit the molded form of the 90 stiffener, tapering at both ends and having an oblique transverse slit near its forward end into which the stiffener passes, the material of the shank body in the center being 95 shaped to fit the last bottom and fill the shoe bottom from seam to seam thus providing a 100 surface shaped for supporting the insole.
